United States Patent Office

Des. 184,846
Patented Apr. 14, 1959

184,846

LUGGAGE CASE

Willard G. Axtell, Englewood, Colo.

Application February 4, 1957, Serial No. 44,728

Term of patent 14 years

(Cl. D87—5)

FIG. 1.

FIG. 2.

FIG. 3.

FIG. 4.

Fig. 1 is a top plan view of a luggage case embodying my new design;

Fig. 2 is a side elevation of the luggage case of Fig. 1;

Fig. 3 is an end elevation of the luggage case;

Fig. 4 is a bottom plan view of the luggage case, and

Fig. 5 is a fragmentary cross-section, on an enlarged scale, of one edge of the luggage case.

I claim:

The ornamental design for a luggage case, as shown.
